UNITED STATES PATENT OFFICE

ISAAC A. BAUM, OF CHICAGO, ILLINOIS

WINDOW SILL

Application filed February 27, 1930. Serial No. 431,766.

My invention relates to buildings and particularly to a novel window frame construction.

An object of my invention is to provide a window frame having a sill and stool of novel form and arrangement. A difficulty heretofore experienced in the construction of all-metal window frames has been to provide suitable means for attachment of the sill to the adjacent supporting wall. In the construction here described, I provide for this feature and insure a satisfactory, attractive and efficient arrangement.

In metal frames of this character it is essential that the sill be formed of sheet metal and, as the sill must of necessity have a certain contour and a decided slope as to its upper outward face, the space there beneath is necessarily hollow and must be filled with a plastic material such as concrete or mortar. Due to this fact difficulty has been experienced in filling this space after the frame has been installed. If an attempt is made to set the sill on a bed of mortar there is always an uncertainty as to whether the space is filled and there is the further uncertainty as to the rigidity and accuracy of the mounting.

I avoid these objections by providing the sill with numerous openings or cut-out portions in its upper surface, thus enabling the mounting of the sill in an exactly predetermined position, securing it in place by means of screws which are accessible through the openings, and thereafter filling the space with concrete, leveling and painting it at the exposed points. The portion of the sill that might be objectionable if the cut-out portions were left exposed is covered by a stool that may be applied after the frame has been permanently located.

The invention will be more readily understood by reference to the accompanying drawings, in which

Fig. 1 is a plan view of a window sill constructed in accordance with my invention;

Fig. 2 is a sectional view through a mounted and completed sill; and

Fig. 3 is an enlarged fragmentary perspective view of one end of the sill showing the means provided for interlocking with a side member.

In the drawings, it will be seen that the sill is of generally channel shape having a web 10 with an upstanding rib 11 therein, thereby forming a seat 12 for the bottom member of a sash, not shown. At the two sides I provide downturned flanges 13-14, the latter having its margin 15 bent at right angles and adapted to receive screws 16 that serve to secure the sill in a desired position.

At intervals I provide cut-outs 17-18-19 in the surfaces 10-11-12 to facilitate the application of a plastic material such as concrete, indicated at 20. The plastic material may be conveniently forced into place and packed securely into the space beneath the web and thereafter carefully leveled to conform to the outer surface of the sloping portion 10 which will be normally exposed to the weather.

A plaster terminal member 21 is secured to the surface of the flange 13 and serves to define the plaster limit on the inside of the frame. As a means for covering and trimming the inner surface of the sill, I provide a metal stool consisting of a web 22 one edge of which is bent to provide the vertical portion 23 and the horizontal covering 24 that overlies the rib 11 and the cut-outs therein. The opposite edge of the web is downwardly and backwardly bent as at 25-26 to snugly fit over a U-shaped clip 27 that is welded to the flange 13. Screws 28 passing upwardly from beneath the overhanging portion of the stool serve to form a rigid fastening for the inner portion of the stool. Screws 29 serve a similar purpose for the forwardly projecting edge of the stool. The metal stool element may be shaped as desired to conform to the architect's design, the angular construc-

tion here illustrated being selected for simplicity. This stool member serves to cover the openings 18—19 in the sill that might be considered to be unsightly.

- 5 The sill member as shown in Figs. 1 and 3 will preferably be installed and permanently mounted, together with side and head frame members, not shown, that are provided with interlocking corner connections. A 10 connection for a side member is illustrated in Fig. 3 and comprises plates 30 having tongues 31 that are welded to the flanges 13—14, the plates being joined by a channel 32. Vertical flanges 33 formed on the plate 30 are 15 adapted to cooperate with suitably formed sockets on the side member. The form of the corner connection is illustrated and described in my copending application Serial No. 481,764, filed of even date herewith.
- 20 Obviously the construction is capable of some modification and I do not wish to be limited except as indicated in the appended claims.

I claim:

- 25 1. A sill for metal window frames comprising in combination a sheet formed to provide a seat for a sash and having downturned marginal flanges, the sheet being cut away at intervals to facilitate the filling of the space 30 beneath the sill with plastic material. 95
2. A sill for metal window frames comprising in combination a sheet formed to provide a seat for a sash and having downturned marginal flanges adapted to space the sill above 35 a support, the sheet being cut away at intervals to facilitate the filling of the space beneath the sill with plastic material. 100
3. A sill for metal window frames comprising in combination a sheet formed to provide 40 a seat for a sash and having downturned marginal flanges adapted to space the sill above a support, and fastening devices for securing a flange to said support, the sheet being cut away at intervals to facilitate the application 45 of said fastening devices and the filling of the space with plastic material. 105
4. A metal window sill comprising in combination a channel shaped member, the web of which is formed to provide a sash seat, 50 said web having cut-out areas to facilitate the filling of the space beneath the web with plastic material, and a separate member secured to the sill and adapted to trim the inner exposure of the sill. 110
- 55 5. A metal window sill comprising in combination a channel member, the web of which is formed to provide a sash seat, said web having cut-out areas to facilitate the filling of the space beneath the web with plastic 60 material, a separate member secured to the sill and adapted to trim the inner exposure of the sill, and to cover some of said cut-out areas. 115
6. In a metal window sill, the combination 65 of a plate of inverted channel shape in cross 120

section, the web of the channel being cut away at intervals, and a separate metal member adapted to interfit with and be secured to the sill after it is installed and to provide interior trim for the sill. 70

7. In a metal window sill, the combination of a plate of inverted channel shape in cross section, the web of the channel being cut away at intervals, and angular projections from an end of the sill adapted to interfit 75 with side members of a frame.

In testimony whereof I have affixed my signature.
